UNITED STATES PATENT OFFICE.

JOHN L. KRAUSER, OF READING, PENNSYLVANIA.

MANUFACTURING NAILS.

Specification of Letters Patent No. 21,005, dated July 27, 1858.

To all whom it may concern:

Be it known that I, JOHN L. KRAUSER, of the city of Reading, in the county of Berks and State of Pennsylvania, have invented 5 certain new and useful Improvements in Nail-Plates for the Manufacture of Improved Cut Nails; and I do hereby declare that the following is a full and exact description thereof, reference being had to the 10 accompanying drawings and to the letters of reference marked thereon.

The object of my invention is the production of an improved point upon that description of cut nails whose two rolled sides 15 are parallel, and whose cut faces are tapering from head to point. Its nature consists in so beveling the edges of nail plate that the blanks cut therefrom will be tapering or V shaped at both ends; the head being formed 20 by driving the heading tool against the widest of the tapering extremities; the details being as hereinafter set forth.

To enable others skilled in the art to make and use my invention, I will proceed to 25 scribe its construction and operation.

The usual method of preparing nail plates for the production of cut nails consists in introducing to a shears of the requisite form and construction, a sheet of metal of any 30 length, it being of the requisite thickness, and breadth, from which by a transverse cut, are severed strips of the required width, and length, forming what is commonly termed the nail plate, such plate being uniformly 35 produced with (practically speaking) square edges, and from which are afterward cut the blanks, which when headed, form the well known cut nail, with blunt ends or extremities.

40 The object of my improvement is so to prepare the plate, that when the blanks are cut therefrom, and headed the same shall be pointed without further process. To accomplish this I prepare the plate with tapering 45 or V shaped edges as indicated by letters *c, c*, Figure 1, which is an end view of the improved plate taken through the dotted

lines *a, a*, in Fig. 2, which latter figure is a perspective view of the improved plate. It will be observed that if the tapering edges 50 *c¹, c²*, Fig. 2, of the plate be made continuous on both sides of the plate, that the blanks, Figs. 4 and 5, cut therefrom will previous to the heading thereof, be wedge or V shaped at both extremities, *b, b¹*, so that in the 55 process of heading the same, the heading tool must act against the wedge, *b¹*.

The object of my improvement therefore has reference to the production of cut nails and spikes which shall be provided with 60 tapering, wedge or V shaped ends or extremities and which is accomplished by treating the nail plate in manner as hereinbefore explained.

This method of forming cut nails with 65 sharp points differs from that employed in making horse shoe nails, as the plate in that case is rolled to a sharp edge on one side only, the two faces inclining to each other for that purpose. This process differs also, 70 from the manner of pointing shoe pegs; there being no heading there, and all the opposite sides parallel.

I do not claim rolling nail plate to an 75 edge on one side by inclining its faces as is practiced in making horse-shoe nail blanks; nor, do I claim sharpening a single edge, as in the strips of wood from which shoe pegs are split, as my invention is altogether distinct from these cases; but 80

What I do claim and desire to secure by Letters Patent, is—

The process as herein set forth, of making cut nails with improved points; that is to say—beveling both edges of the nail plate 85 so that the blanks shall be wedge shaped at both ends, as shown in Fig. 2, and forming the head by the action of the heading tool against the widest end of the blank, as hereinbefore set forth.

JOHN L. KRAUSER.
